HIGH INTENSITY LAMP

Dan M. Andre, 8843 Kostner Terrace,
Skokie, Ill. 60076

Filed Nov. 18, 1966, Ser. No. 4,739

Term of patent 14 years

Int. Cl. D26—02

U.S. Cl. D48—20

FIG. 1 is a perspective view of a high intensity lamp illustrating my new design;

FIG. 2 is a side elevational view of the same;

FIG. 3 is a front elevational view of the same;

FIG. 4 is a top plan view of the said lamp;

FIG. 5 is a rear elevational view of the same;

FIG. 6 is a side elevational view of said lamp showing the shade and its mounting pole in the lowered position.

The dominant features of my design reside in the portions shown in full lines.

I claim:

The ornamental design for a high intensity lamp, as shown and described.
